UNITED STATES PATENT OFFICE.

ISAAC E. PALMER, OF MIDDLETOWN, CONNECTICUT.

HAMMOCK-SUPPORT.

SPECIFICATION forming part of Letters Patent No. 665,125, dated January 1, 1901.

Application filed April 29, 1898. Serial No. 679,179. (No model.)

To all whom it may concern:

Be it known that I, ISAAC E. PALMER, a citizen of the United States, and a resident of Middletown, in the county of Middlesex and State of Connecticut, have invented a new and useful Hammock-Support, of which the following is a specification.

My invention relates to a hammock-support, with the object in view of providing a light stable support which may be folded into a compact compass for shipment or storage and which may be readily set up for use as occasion may require.

A practical embodiment of my invention is represented in the accompanying drawings, in which—

Figure 1 is a view of the support in side elevation as it appears when set up for use. Fig. 2 is a view of the same in end elevation. Fig. 3 is a top plan view of the same. Fig. 4 is a view of the support when folded looking at it in the direction toward which the folded legs face. Fig. 5 is a view of the same looking at it in a direction edgewise of the folded legs or at right angles to the position shown in Fig. 4. Fig. 6 is an end view looking toward the foot ends of the folded legs. Fig. 7 is an end view looking toward the folded joints of the legs. Fig. 8 is an enlarged view in detail, showing the exterior of the leg-joint as it appears when the support is set up for use. Fig. 9 is an edge view of the same. Fig. 10 is a view of the same from the inner or under side. Fig. 11 is a view of the same taken from a point of view corresponding to that represented in Fig. 9 and showing the parts in their folded adjustment. Fig. 12 is an end view of the folded parts represented in Fig. 11. Fig. 13 is an enlarged view in detail, showing in side elevation the joint in the backbone or ridge-pole, the parts being shown in assembled adjustment as in use. Fig. 14 is a top plan view of the same. Fig. 15 is a view of the same in side elevation, showing the parts in their folded adjustment. Fig. 16 is an end view of the same. Fig. 17 is an enlarged view in detail in side elevation, showing the joint between the legs and the backbone or ridge-pole and showing the parts in assembled adjustment as in use. Fig. 18 is an end view of the same. Fig. 19 is a top

plan view of the same. Fig. 20 is a view of the same, showing the legs in their folded adjustment. Fig. 21 is a view in detail in side elevation, showing a modified joint for connecting the legs with the backbone or ridge-pole; and Fig. 22 is an end view of the same, the parts in Figs. 21 and 22 being shown in assembled adjustment as in use.

The sections of the backbone or ridge-pole are denoted by A A'. In the present instance the entire ridge-pole is composed of two sections; but it might be formed in more than two, if so desired. Each of the sections A A' consists of longitudinal bars $a a'$, spaced apart and connected at their opposite ends by suitable castings, which castings are also adapted to form parts of joints, as will hereinafter more particularly appear. I have shown the bars $a a'$ of each of the sections arranged substantially parallel throughout the length of the section, and this arrangement I find to be very rigid and efficient in practice. The sections A A' are hinged together in a manner which will permit one of the sections A or A' to be swung underneath the other section, so that the two sections shall lie when folded edgewise in the same plane, as clearly indicated in Figs. 15 and 16.

The hinge-joint between the two sections is preferably formed as follows: A pair of castings B B', each provided with half-sockets $b b'$, spaced apart a distance corresponding to the distance between the bars $a a'$ of the sections, receive between them the ends of the bars $a a'$ and are tightly drawn together to press the ends of the bars between them by means of bolts b^2 , provided with nuts b^3 . At their lower ends the castings B B' are each provided with a perforated ear, (denoted, respectively, by $b^4 b^5$.) Castings similar to B B' are in like manner engaged with the adjacent ends of the bars $a a'$ of the adjacent section of the ridge-pole and are provided with perforated ears $b^6 b^7$, arranged to register with the perforated ears $b^4 b^5$, and through these perforated ears when arranged to register there extends a hinge-pintle b^8 . The sections A A' of the ridge-pole so hinged together may be conveniently locked in extended adjustment by means of a swinging loop b^9 , caught at one end in eyes b^{10} at the top of the

castings B B' and at its opposite end provided with an opening b^{11} for the reception of upwardly-extending lugs $b^{12} b^{13}$ at the adjacent upper edges of the pair of castings at the ends 5 of the sections. The position of the fastening-loop b^9 when in locked adjustment is clearly shown in Figs. 13 and 14 and when in released adjustment in Fig. 15.

The ridge-pole is supported by four legs 10 arranged in pairs at its opposite ends. The four legs are similar to one another and the specific description of one and the manner of connecting it to the ridge-pole will disclose fully the structure and manner of connection 15 of the others. The connections at the opposite ends of the ridge-pole sections form at the same time a connection between the bars of the ridge-pole section and one part of the hinge-joint between the ridge-pole section and the leg. Referring to the enlarged views in detail in Figs. 17 to 20, inclusive, a pair of castings, the members of which are denoted by C C', are each provided with half-sockets c^c , spaced apart a distance corresponding 20 to the space between the bars $a' a'$ of the section and are fitted to tightly embrace the opposite sides of the bars $a' a'$. They are drawn snugly into contact with the bars and held in position by means of bolts c^2 , provided 25 with nuts c^3 . These castings C and C' are further provided intermediate of the half-sockets with a lug c^4 , having a head tapered on its inner or under side, and at their lower ends each of the said castings is provided 30 with a downwardly and laterally projecting tongue c^5 . One of the castings—as, for example, the casting C—is also conveniently provided with a hook c^6 for the attachment thereto of one end of the hammock. (Not 35 shown.) The leg comprises two sections—an upper and a lower section—the upper section being denoted by D and the lower section by D'. The upper section of the leg is preferably formed of a pair of bars (denoted by d 40 d'), which gradually diverge from the lower end of the section D toward the ridge-pole, and at their upper ends they are connected by a casting (denoted as a whole by E) provided with a pair of half-sockets $e e'$ for the 45 reception of the ends of the bars $d d'$, respectively. The ends of the bars $d d'$ are held in the half-sockets $e e'$ by means of an exterior plate E', also provided with half-sockets $e^2 e^3$, the plate E' being clamped to 50 the plate E to hold the ends of the bars $d d'$ snugly between them by means of bolts e^6 , provided with nuts e^7 . The casting E is further provided with a web e^8 , connecting the half-sockets $e e'$ intermediate of the position 55 which the bars $d d'$ occupy and so shaped as to receive the locking-tongue c^5 on its face, as clearly shown in Fig. 17, when the parts are assembled for use. The casting E is further provided with a vertically-elongated 60 slot e^9 for the reception of the stem of the lug c^4 , the outer portion of the slot e^9 having its

walls beveled, as shown at e^{10} , to conform to the tapered inner face of the head of the lug c^4 , so as to form a close engagement with the lug when the lug occupies the lower position 70 within the elongated slot e^9 as when weight is applied to the ridge-pole when the latter is set up for use. The arrangement of the lug c^4 with respect to the plate e^8 is such that the tongue c^5 will engage the plate e^8 simultaneously with the engagement of the lug c^4 with the beveled wall e^{10} of the slot e^9 , so as to effect a tight lock between the leg and the ridge-pole when the latter is set up for use, the greater the weight applied to the ridge-pole 80 the firmer the lock, and at the same time permitting the unlocking of the parts the moment weight is removed by simply lifting the end of the leg from the ground or floor and sliding it lengthwise far enough to disengage 85 the tongue c^5 from the plate e^8 . Such movement of the leg will be permitted by the elongated slot e^9 , and when the tongue is released from the plate the leg may be swung edge-wise into a plane parallel with the plane of 90 the backbone-section adjacent thereto, as shown in Fig. 20.

Instead of beveling the wall of the slot e^9 the casting E may be provided at its upper end with a tongue e^{11} , as shown in the modified form, Figs. 21 and 22, which may be received beneath a keeper e^{12} on the casting C. 95

The sections D and D' of the leg are hinged together, so that the section D' or lower section may be folded outwardly over onto the section 100 D. The lower section D' is preferably formed of a single piece of material and having its upper portion separated into diverging bars d^2 d^3 , the former being so arranged as to form a continuation of the bar d of the upper section 105 D of the leg and the latter, d^3 , to form a continuation of the bar d' of the upper section. The two sections are hinged together by means of castings F F', each provided with a pair of half-sockets the members of which are 110 denoted by $f f'$ and are spaced apart a distance corresponding to the space between the bars $d d'$ and $d^2 d^3$. The casting F is provided with a pair of perforated lugs $f^2 f^3$ and the casting F' with a pair of lugs $f^4 f^5$, arranged to register with the lugs $f^2 f^3$, and the hinge is completed by a pintle f^6 , which extends through the registering lugs aforesaid. 115 The castings F F' are each secured to the end of its respective leg-section D by means of a clamp-plate f^7 , which engages the outer faces of the bars near the ends of each of the sections, which plate is drawn in snug contact with the leg-sections by means of a bolt f^8 , provided with a nut f^9 . The leg-sections D 120 D' are conveniently locked in their extended adjustment by means of a hook G, pivotally secured to one of the castings, as F, and adapted to swing into and out of engagement with an eye g , fixed to the other casting F'. 125

In speaking of the several half-socket pieces as "castings" I have used a term which is 130

strictly applicable to them as castings, a form which is found to be efficient and economical; but I do not in using such term wish to be understood as limiting the joint-pieces to metal which is actually cast as distinguished from being swaged or struck up by dies, as it may be found expedient to resort to such manner of forming the pieces in order to save weight and at the same time preserve the necessary strength.

To fold the support from the position shown in Figs. 1, 2, and 3 into the folded adjustment shown in Figs. 4, 5, 6, and 7, the lower section D' of each of the legs may first be folded over onto the upper section by releasing the hook G from the eye g. Each of the legs thus folded may then be dropped sufficient to release it from its locked engagement with the end of the backbone and when so released swung around into position to lie alongside of the backbone-section adjacent thereto, as clearly indicated in Fig. 20. The backbone then may be released at its joint by throwing the loop b⁹ out of engagement with the lugs b¹² b¹³, and the backbone-sections may then be, together with the folded leg-sections, folded together, bringing the whole mass into the compact compass represented in the different views, Figs. 4 to 7, inclusive.

In the folding for shipment or storage and in the unfolding to set the supports in position for use there is no occasion for either hammer, screw-driver, or wrench and there is no liability of any part being lost or misplaced, as they are all connected and remain so in their folded adjustment, as well as when set up.

It will be further observed that there is no liability of the bars which form the backbone and the parts which form the legs working loose or escaping from their socket-pieces, since each of the sockets in which they are held is of the two-part structure and provision made for drawing these two parts into close contact with the bars and parts of the leg. The structure, furthermore, saves the exact fitting required in fitting a bar to enter a complete socket, and if at any time there should be shrinkage sufficient to cause the slightest looseness this may be promptly taken up and made as rigid as in the beginning by simply turning the nut on the draw-bolt, which draws the two parts of the socket toward each other.

To limit the spread of the legs, I find it convenient to fasten a cord H at one end to one of the legs, as at h, and lead it thence through a slot in the bottom of the leg across to the opposite leg, where it may be inserted in a slot and prevented from becoming displaced by means of a knot h' or other stop located in such a position as to determine the proper spread of the legs. When so adjusted, it forms a tie, preventing any liability of the legs spreading under pressure and may be

utilized when the parts are folded to tie them together.

I find it convenient to provide one of the backbone-sections A A', in the present instance A, with a sliding supporting-ring I, 70 having a hook i thereon. The fit of the hook I is such that when strain is placed upon the hook i it will tend to tilt the ring I and cause it to bind on the bar a' sufficiently to hold it in any position in which it may be placed 75 along the bar a'.

It is evident that changes might be resorted to in the form and arrangement of the several parts described without departing from the spirit and scope of my invention. Hence 80 I do not wish to limit myself strictly to the structure herein shown, but

What I claim is—

1. A hammock-support comprising a folding backbone, supporting-legs arranged in 85 pairs and forming the main support of the backbone, each of the legs being formed in sections hinged together for folding the lower section onto the upper section and joints forming a permanent connection between the 90 legs and the backbone, means for permitting the said legs to swing bodily toward and away from the backbone in a plane parallel with the longitudinal axis of the backbone and the upper members of each pair of legs being, at 95 the same time, free to move toward and away from the backbone into and out of locking engagement with the backbone, substantially as set forth.

2. A hammock-support comprising a backbone consisting of bars spaced apart throughout their length, legs arranged to support the backbone and joints connecting the legs with the backbone, the said joints consisting of spacing-pieces for the backbone-bars and 105 hinge-pieces connected with the spacing-pieces for the attachment of the legs, substantially as set forth.

3. The combination with a backbone, of legs for supporting the backbone and a joint 110 between the leg and the backbone, the said joint consisting of interlocking parts, the one of said parts being provided with a holding-tongue and a stud and the opposite part being provided with an incline-faced bearing- 115 plate for engaging the tongue and with a vertically-elongated slot for the reception of the stud, substantially as set forth.

4. The combination with a backbone, of legs for supporting the backbone and a joint 120 for connecting the leg with the backbone, the said joint consisting of interlocking parts one of said parts being provided with a holding-tongue and a stud and the other part being provided with a bearing-plate for engaging 125 the tongue and an elongated slot having its walls beveled for engaging the stud, substantially as set forth.

5. The combination with the backbone and its supporting-legs, of a joint for connecting 130

the backbone and leg, one of the parts being provided with a tongue and a stud having a beveled head, the other part being provided with a bearing-plate and elongated beveled 5 wall-slot for engaging the said tongue and stud, substantially as set forth.

In testimony that I claim the foregoing as

my invention I have signed my name, in presence of two witnesses, this 27th day of April, 1898.

ISAAC E. PALMER.
